CONVERTIBLE HAT

Marianne Tuteur, New York, N. Y., assignor to
Talon, Inc., a corporation of Pennsylvania

Application April 5, 1952, Serial No. 19,200

Term of patent 7 years

(Cl. D3—13)

To all whom it may concern:

Be it known that I, Marianne Tuteur, a citizen of the United States, residing at New York, in the county and State of New York, have invented a new, original, and ornamental Design for a Convertible Hat, of which the following is a specification, reference being had to the accompanying drawing, forming a part thereof.

In the drawing:

Fig. 1 is a top view of a convertible hat showing my new design;

Fig. 2 is a front view of the convertible hat shown in Fig. 1;

Fig. 3 is a side elevational view thereof, and Fig. 4 is a bottom view thereof;

Fig. 5 is a front view of the convertible hat as it appears in unzipped position with the feather-like portion exposed;

Fig. 6 is a side elevational view thereof; and Fig. 7 is a sectional view thereof taken on line 7—7 of Fig. 6.

I claim:

The ornamental design for a convertible hat, substantially as shown.

MARIANNE TUTEUR.
